UNITED STATES PATENT OFFICE.

ORA DWANE HARDEN, OF CHICAGO, ILLINOIS, ASSIGNOR, BY MESNE ASSIGNMENTS,
OF ONE-HALF TO CHARLES E. SUMMERS, OF CHICAGO, ILLINOIS.

ELECTROTYPEING-CASE POLISHER.

1,418,074.

Specification of Letters Patent. Patented May 30, 1922.

Application filed March 11, 1921. Serial No. 451,646.

To all whom it may concern:

Be it known that I, ORA D. HARDEN, a citizen of the United States, residing at Chicago, in the county of Cook and State 5 of Illinois, have invented certain new and useful Improvements in Electrotyping-Case Polishers, of which the following is a specification.

The invention relates to improvements in 10 electrotyping case polishers.

One of the objects of the invention is to provide improved means for coating and polishing or burnishing wax cases or matrices used in electrotyping.

15 Another object is to provide improved means for applying powdered graphite, plumbago, black lead, or the like, to the surfaces of the wax forms or matrices, usually called wax cases, preliminarily to copper- 20 plating the exposed surfaces thereof in the process of making electrotypes, and for reclaiming the excess of the powdered material that does not adhere to the wax surfaces, which otherwise would be blown off the 25 form as a result of the usual manner of cleaning the coated surfaces after being polished.

The usual manner of applying the powdered electro-conducting material to the 30 surfaces of the wax cases is not only wasteful but exceedingly untidy, because the very fine powder when blown off the case floats around the room and finally settles as very objectionable dust on all exposed objects.

35 It is furthermore objectionable on account of its color and the tenacity with which it adheres to one's hands, face and clothing.

Other, further and more specific objects 40 of the invention will become readily apparent to persons skilled in the art, from a consideration of the following description when taken in conjunction with the drawings, wherein:—

Fig. 1 shows in elevation parts of the invention for carrying it into effect.

Fig. 2 is an enlarged horizontal section through the longest axis of the brush.

Fig. 3 is a similar section of the aspirator used for attenuating the air within the confines of the bristles of the brush.

In all of the views the same reference characters are employed to indicate similar parts.

A brush 5 has a back 6 and tufts of bristles 7, secured to the brush back. These

bristles are soft and of fine quality so as not to scratch or otherwise injure the rather soft wax surfaces with which they are brought into contact when in use. A soft rubber band, or other air-proof, yielding 60 material, 8, is placed around the back 6 and the bristles 7. It does not quite reach the bottom ends of the bristles so as to leave these ends free for contact with the wax surfaces. 65

A series of small air tubes 9 extends through the back 6 into the midst of the body of bristles, their lower ends being open, their other ends all communicating with an air tube 10, the reduced end 11 of 70 which is connected by a flexible hose 12 with the fitting 13 of the aspirator 14. Communicating with the hose 12, through the fitting 13, is a bore 15 closed at one end. This bore is bisected at right angles by a two-part bore 16 into which is threaded a pipe 17. The lower end of the pipe 17 is shown connected to a short section 18 of larger pipe and to this is connected a filter bag 19. Extending axially of the bore 16, on the opposite side of the bore 15, is a hub 20 within 75 which is fixed a small tube 21, the inner end 22 of which extends into the inner end of the pipe 17. A valve 23 is screwed to the end of the hub 20 and to the end of the 80 valve a hose 24 is connected. This hose is to be connected to any suitable source of compressed air.

To use the device the brush 5 is dipped into a vessel or pan containing graphite. 90 The amount that adheres to the protruding ends of the bristles 7 is applied to the wax form or case and evenly distributed to the surfaces thereof. The brush may be dipped into the graphite until sufficient quantity 95 has been applied to the case to thoroughly cover it. Then the brush is rubbed frequently over the surfaces to produce a burnished effect known as polishing. In applying the graphite there is always an excess 100 quantity that does not adhere to the form. To remove the loose graphite the valve 23 is opened, whereupon air passing thru the small tube 21 into the larger pipe 17 produces, by aspiration, a suction effect, or attenuation of air in the bore 15, the hose 12 and throughout the bristles 7 of the brush under the rubber housing 8 which draws the air into the pipes 17 and 18 from which 105 it is projected into the filter bag 19. Any 110

of the loose powdered material in contact with the lower surface of the bristles will be drawn into the aspirator and projected with the air into the filter bag.

5 If the brush is placed over the loose powder on the form or case it will all be drawn up and deposited in the bag leaving the case clean and reclaiming all of the graphite that did not closely adhere to the 10 surfaces of the case.

The device could as conveniently be used for distributing and applying other powders when used for other purposes and for taking up and reclaiming the loose unused powder 15 15 in the manner described.

While I have herein described a single embodiment of the invention for the purpose of clear disclosure, it will be manifest, to persons skilled in the art, that various 20 changes in the configurations and dispositions of the parts can be made within the spirit and scope of the appended claims.

Having described my invention what I claim as new and desire to secure by Letters 25 Patent, is:—

1. In a device of the character described, the combination of a brush having a back with a body of bristles connected thereto; a row of centrally disposed tubes extending 30 through the back into the body of bristles; a centrally disposed pipe, secured to the back, in which the tubes terminate; a yielding air-

proof housing, extending around the back and around the bristles and terminating above the free ends of the bristles, whereby 35 to draw air and small material particles through the brush bristles when the air in the pipe is attenuated and an aspirator connected to said pipe.

2. In a device of the character described, 40 the combination of an aspirator comprising a fitting having a bore closed at one end, the open end being connected by a hose to a brush, and having a transverse, through and through, two-part bore, bisecting the first 45 mentioned bore; a pipe in one part of the two-part bore connected to a filter bag; a tube in the other part of said two-part bore extending into said pipe; means for connecting a source of compressed air to said tube; 50 a brush having a back; a body of bristles extending from one side thereof; an air pipe secured to the back and communicating through the back with the body of bristles and a housing of soft rubber extending 55 around the edge, of the back, and around the body of bristles, terminating above the free edges of the bristles, whereby to draw air and particles through the body of bristles of the brush when compressed air is introduced 60 into said tube.

In testimony whereof I hereunto subscribe my name.

ORA DWANE HARDEN.
